SELF FEEDING CARBURETOR

Wilfred O. Chase, Detroit, Mich.

Application June 30, 1934, Serial No. 733,215

Renewed October 10, 1936

23 Claims. (Cl. 261—34)

The object of this invention is to make a carburetor in which the fuel is automatically raised to the fuel nozzle without the use of a fuel pump. In other words, a carburetor of the type generally known in the trade as a self feeding carburetor.

Fig. 1 shows a cross sectional elevation on the plane 1—1 of Fig. 2.

Fig. 2 is an outside elevation of the carburetor. Fig. 3 is a modified view of a portion of Fig. 1 showing the position of the moving parts when the throttle is in the wide open position.

Fig. 4 is a partial cross sectional plan view on the plane 4—4 of Fig. 1.

Fig. 5 is a cross sectional plan view on plane 5—5 of Fig. 1.

Fig. 6 is a cross sectional plan view taken on plane 6—6 of Fig. 1.

Fig. 7 shows diagrammatically in elevation the principal fuel and air passages in the carburetor.

Description

Considering first Figure 7, the air entrance 11 in the carburetor body 93, is shown controlled by an air valve 12. This air valve floats in the air stream and engages with the lip 105 of the fuel outlets 35 and 34 which are connected together through a cross passage 33. The valve 12 is guided in a cylinder 13 which is supported by arms 14 in the air entrance 11. A disc 15 supported on a rod 16 is guided inside the cylinder 13 and on the rod 16 engaged with the air valve 12. The shoulder 17 engages with the arm 18 of a lever 19 supported on a pivot 20 and thus gives a manually operated control for either limiting the opening or completely closing the air entrance between the lip 105 and the cylinder valve 12. The air valve as stated above is arranged to float in the air stream, the means whereby it floats comprising a rod 21, a disc 22 and a disc 23. These two discs move in tapered fuel passages 24 and 25. Fuel is supplied to the upper tapered fuel passage 24 by means of the horizontal passage 47 located in a bridge 99 in the main air passage. This horizontal fuel passage 47 obtains its fuel from the fuel chamber 67, through the fuel passage 41 and past the spring check valve 65, which is spring loaded. The fuel passage 47 communicates through a small passage 79 with the upper part of the fuel chamber 67 through the fuel passage 77, there being a check valve 78 provided in the fuel passage 79 between the passages 77 and 47. There is a lower passage 38 for mixed air and fuel communicating

with the lower tapered fuel passage 25 through a passage 37 located in the bridge 99 located in the main air passage. This passage 38 communicates with an air entrance 71, through a passage 104—75 past a tapered plug 73 which controls the area of the opening from the atmosphere leading to the passage 38. This tapered valve 73 is supported on a flexible diaphragm 70 which in its turn is supported on a coil spring 68 in a spring retainer 69 and located in the fuel chamber 67. Concentric with the tapered valve 73 which is guided in the plug 74 is another valve 86 which acts as a cut-off valve between a fuel passage 85 and the fuel chamber 67. This fuel passage 85 obtains its fuel through pipe 91 (Fig. 2) from a fuel tank at a lower level commonly known as a fuel tank of a car. Atmospheric pressure is applied on an upper portion of the diaphragm 70 through a small opening 111 in the cover over the diaphragm 70, which cover is held in place by screws 94.

Low speed fuel supply passages are provided which connect the fuel passage 47 (see Fig. 1) to the passage 28 controlled by an adjustable screw plug 27. The passage 28 discharges into the mixture outlet on the engine side of throttle 31 through opening 30. The main running mixture is obtained from the air flowing through the entrance 11 and the fuel which flows beneath the lip 105 and then mixes with the air flowing past the air valve 12. This mixture passes down both sides of the bridge 99 in which is located the passages 26 and 37 and so through the mixture chamber 100 to the engine side of the throttle valve 31. The carburetor is adapted to be bolted to an inlet manifold not shown by means of a flange 92.

In the carburetor as actually made, it has been found necessary to add a few extra parts as shown in Figures 1 to 6. Describing the carburetor as illustrated in Figures 1 to 6, with particular reference to the various control parts added, 11 is the air entrance which provides air which flows by the floating air valve 12, guided in the cylinder 13 which is supported by the arm 14 in said air entrance 11. This air valve controls the fuel issuing from the fuel passages 34 and 35 under the lip 105 which acts as a spreader for the fuel entering the air stream. The disc 15 controlled by a shaft 16 enables the air valve 12 to be closed by a manually controlled lever 19 supported on the shaft 20 engaging through an arm 18 with a shoulder 17 mounted on a shaft 16. For obvious reasons the disc 15 is provided with

perforations 15'. The floating air valve 12 is guided on the shaft 21 which carries the two discs 22 and 23 which float in the tapered fuel passages 24 and 25. The fuel passage 26 communicates through the passage 41 with the horizontal passage 46 which in its turn communicates with the annular tapered passage 45 located in the movable piston 101. Fuel flows from the fuel chamber 67 through the outlet 66 past the check valve 65 thru the passage 41 to the piston 101 past the check valve 42 which rests on the annular seat 43. The check valve 65 is controlled by the spring 64 and guided in the screw plug 62 by means of the guide 63. Two openings 44 in the piston 101 allow fuel to flow into the tapered passage 45. The fuel flows also to the upper part of the cylinder in which this piston 101 reciprocates through the piston 101 in which passages 60 are provided, and escapes from the upper part of the cylinder through a plug 103 which is provided with passages, specifically with the passage 59 which communicates with the passage 55 in the plug 103 which discharges into the annular passage 54 and clearance chamber 52 which in its turn communicates with the passage 53 which leads to a passage 51, which passage 51 also communicates with the passage 26.

The plug 103 is also provided with the passage 56 which communicates through a chamber 57 and a passage 58 with the air entrance 11. These passages 56 are also in communication with the fuel passages 55 and the annular passage 54. In this arrangement the passage 55 can either supply fuel to 26 or supply air as the case may be. Referring to Figure 5, it will be noticed that there is a passage leading around the cylinder in which the piston 101 reciprocates. This passage is numbered 48-49 and communicates through a passage 50 with the vertical cylindrical passage 40 which is in alignment with and a continuation of the cylinder 104. This passage 40 is controlled by a piston valve in the form of a tapered plug 40'. The passage 40 and 104 communicates with the horizontal passage 75 which in its turn communicates with the passage controlled by the tapered plug 73 which is guided in the cap 74. The orifice controlled by the tapered plug 73 is numbered 72 and the air flow through the restricted opening 72 is obtained by the passage 71 which communicates with the air entrance 11. A bypass air passage 76 is provided leading from the horizontal air passage 75 to the lower portion of the vertical passage 40. The second tapered fuel passage 25 in the bridge 99 across the air inlet 11 communicates through a horizontal passage 37 through another horizontal passage 38 (see Figure 6), 38' through a passage 39 with the lower portion of the vertical passage 40.

The fuel supply for the engine is obtained through the large opening 85 which communicates with the fuel tank, not shown. The fuel flows by the shut-off valve 86 which is suspended in the fuel entrance 85 and is controlled by a flexible diaphragm 70. This flexible diaphragm 70 is supported by a coil spring 68 located around the tube 89 which has an outlet opening 90. A fuel entrance 87 is provided which widens out into a fuel passage 88 inside the fuel tube 89 so that the fuel can flow through 90 into the fuel chamber 67. The flexible diaphragm 70 is arranged beneath the wall 93 which creates the chamber 107 which communicates with the atmosphere through the opening 111. The piston

101 which not only serves as a fuel path but also as an accelerating pump is operated by a rod 102, through the fork connection 82, connected by a link 80 to the throttle rod carrying the valve 31 by means of the throttle lever 109 and 5 a pin connection. The pin 81 which goes through the fork and link 80 is also pivotally connected to the rod 84 which has a perforated boss 83. This rod 84 controls the piston 40' which is adapted to reciprocate in the cylinder 10. Air reaches the lower part of the cylinder 40 through the bypass passage 76. The piston 40' thus serves to alternatively connect the air entrance 11 through a passage 71 past the tapered needle 73 and the restricted opening 72 15 with the air fuel passage 75-76-40-39 (see Fig. 6) and through the air fuel passage 75-104 with the passage 50-49-48 and 26 (see Figure 5), both passages communicate with the cross passage 33 which discharges through 34-35 20 beneath the annulus beneath the lip 105.

A vapor outlet consisting of an opening 71, a check valve 78 and a passage 79 which communicates with the fuel passage 41 is provided so that the flow of fuel down 41 allows the vapor to be 25 drawn from the upper part of 67 immediately beneath the diaphragm 70. The atomizing air for low speed flows down 75-104, past the tapered control valve 40' across the passage 50, along the passage 49 across the passage 48 to the 30 passage 26 (see Figure 5) where fuel is admitted from the passage 51. Low speed fuel and air then flows past adjustable screw plug 27 down passage 28 to the mixture outlet on the engine side of the throttle 31, passing through the passage 29 to the low speed fuel outlet 30.

Operation

To start the engine it is assumed that the throttle is opened from the position as shown in 40 Figure 2. In this position the choke lever 19 is raised so as to hold the air valve 12 down on its seat 105 by means of the disc 15. Engine suction then acts through 34 and 35 and communicates through the various gasoline passages with the 45 underside of the diaphragm 70. Atmospheric pressure which enters through 111 into the air chamber 107 presses the diaphragm down and thus unseats the shut-off valve 86. Gasoline then flows up the gasoline passages 87-88 out 50 of the passage 90 into the gasoline chamber 67. The check valve 65 is unseated and gasoline flows down 41 past the gasoline check valve 42 and through the gasoline passages 44 and 45, along 46, up 41, along 26 and so into the tapered opening 24 where it raises the disc 22 which is mounted on the rod 21 which, of course, supports and raises the air valve 12 once the choke valve lever 19 is pushed down so as to release the air valve 12 and to permit it to float in the air stream. 60 Immediately after the engine fires the lever 19 is pushed down and the valve 12 then floats in the air stream, the opening being determined by the gasoline flow by the disc 22. Air is mingled with the fuel in 26 this air being derived from the opening 72 and the passage 50 (see Figure 5) and also from the opening 58 and passage 51. When the throttle is opened the opening connecting 50 with the air passage 104 and 40 is 70 shut off because the piston valve 40' is raised by the rod 84 mounted on the rod 81 which is connected to lever 109 through the link 80 air then enters 39 from the air passage 76. This air is admitted to the air passage 37 (see Figure 6) and air is thus admitted beneath the disc 23. This 75

air tends to cause the disc 23 to float up and to carry with it the air valve 12. This insures an adequate air opening between the annular air valve 12 and the annular fuel orifice which is formed by the inclined lip 105. When the throttle is opened, air flows past the tapered valve 73 to the fuel nozzles 34 and 35. At the same time a quantity of fuel is raised by the pumping action of the piston 101, the fuel caught above the check valve 42 being automatically raised and forced into the carburetor. This provides the fuel needed for accelerating and corresponds to the accelerating pumps that are now in universal use on all modern carburetors.

15 The fuel then flows not only out of passages 44 in the piston 101 but also out of passages 55 in the plugs 103 and 53 into the passage 51 communicating with passage 26 in the bridge 99 so that extra fuel is available for acceleration.

20 Normally when the throttle is in some fixed position fuel flows through passages 44 to passages 46—47—26—24—34 and 35, and air flows down from the air entrance 11 through 71 past the air control valve 73 down either 104 or 76 to either 49 (see Figure 3) or 38 (see Figure 6) depending on whether the air control valve 40 is in the position shown in Fig. 1 or in the position shown in Fig. 3.

30 Correction for lift: The lift required to raise the fuel from the fuel tank to the fuel entrance 85 varies due to:

- (a) variations in grade
- (b) variations in level in the tank.

35 When there is a low level and/or a steep grade the pressure on the underside of the diaphragm is decreased and the valve 73 is restricted because obviously when the fuel is low in the fuel tank or when the car is climbing a hill the level of fuel in the tank in each case is further below the level of the fuel at the fuel nozzle than it is when the car is driving on the level road with the fuel tank full.

40 This decrease in pressure under the diaphragm 70 is communicated through the air and fuel passages 75—104—49—26 and also through the air and fuel passages 75—76—39—38 and 37 to the undersides of the discs 22 and 23. The tendency for the discs to rise in their conical passages 24 and 25 is due to the action of the mixture chamber suction acting on the upper surfaces of the discs 22—23 through 34 and 35. This suction raises the valve 12 which controls the air entrance. Hence as the fuel lift increases the depression in the mixture outlet 100 also increases because the pressure on the underside of the discs 22 and 23 is restricted and hence the resistance to the rise of the air valve 12 is increased. Thus the suction created by the lift tends to hold the air valve shut, and to oppose the tendency of the suction on the upper sides of the discs 22—23 to raise the air valve 12. However, although this depression varies with the fuel lift it is necessary that the proportions of the mixture must not vary with the lift.

45 I have discovered that it is possible by varying the size of the vent 72 by means of the tapering needle 73, that I can maintain the mixture ratio practically constant. In addition to the level variations being used to control the air vent to the fuel nozzle, the throttle itself mechanically controls the admission of air. The additional air regulating means comprising the rod 84 and the tapered valve 40' which alternatively puts the passage 50 and thus passage 26 in communication

5 with the passage 104 (see Figure 5) and puts the passage 39 and thus passage 37 in communication with the passage 16 (see Figure 6) gives the necessary variation in the mixture ratio so that a relatively rich mixture is available at wide open 10 throttle. The function of the opening 77 is to remove any vapor that may form in the upper chamber 67. The shut off valve 86 merely prevents fuel running out of 34 and 35 when the engine is not running in the event that the rear end 15 of the car is raised so as to be higher than the carburetor. In this event the spring 68 will seat the valve 86 and prevent fuel flowing under gravity out of 34 and 35. The two check valves 65 and 78 cooperate to keep vapor out of the fuel chamber 67 and to maintain it full of fuel.

20 When the engine is idling and the throttle almost closed, the port 46 is also closed by the piston 101 and the fuel rises and flows through the passages 60 in the piston 101 passages 55 in 20 the plug 103 and so to port 53 in the plug 103, the idling fuel being mixed with air flowing down air passages 58, 57 and 56 from air inlet 11. The mixed fuel and air flows down passage 51 to passage 26 and so past the idle regulating screw 25 27 down passage 28 through passage 29 to the outlet 30 in the mixture outlet. This ensures a steady flow past the check valve 42 in the piston 101, and it also ensures a full head of fuel up to the port 53 in the plug 103 and this fuel is 30 available when the throttle is suddenly opened for acceleration. If the idle fuel was taken through passage 46 this fuel would not be available for acceleration. The shaft 102 is smaller than the hole through the plug 103 so that wear is not a 35 factor to change the conditions of idling, as air flows down through the air passages 56 parallel to the clearance between the shaft 102 and the passage through which it is guided in 103.

40 I claim:

1. A floatless self feeding carburetor for internal combustion engines comprising a cylindrical air valve, a primary air passage controlled thereby, a fuel supply passage leading thereto, a diaphragm responsive to the pressure in the fuel 45 passage, a fuel outlet discharging into the air entrance on said engine side of the air valve and connected to said fuel supply passage, means responsive to the velocity of flow in said fuel passage for controlling said air valve, valve means 50 for admitting air to said fuel passage, said valve being operatively connected to said diaphragm for the purpose described.

2. A floatless self feeding carburetor comprising a primary air passage, a cylindrical air valve 55 adapted to control said air entrance, a mixture chamber, a mixture outlet, a throttle valve therein, fuel supply means comprising a fuel chamber, a fuel entrance leading thereto, a fuel shut off valve in said fuel entrance, a diaphragm 60 located in said fuel chamber and connected to said shut off valve, a fuel nozzle in said mixing chamber, a fuel passage leading from said fuel chamber to said fuel nozzle, means responsive to the flow of fuel in said fuel passage for controlling the movement of said air valve, valve means 65 for admitting air to said fuel passage, said valve means being operatively connected to said diaphragm.

3. In a carburetor as described in claim 2—an 70 accelerating fuel pump located in the fuel passage leading from the fuel chamber to said fuel nozzle and operatively connected with said throttle.

4. A floatless self feeding carburetor comprising a cylindrical air valve, a primary air passage 75

controlled thereby, a mixture chamber, a mixture outlet, fuel supply means comprising a fuel chamber, a fuel entrance leading thereto, a fuel shut off valve in said entrance, a diaphragm located in said fuel chamber and connected to said shut off valve, a fuel passage leading from said chamber to a fuel nozzle located in said mixing chamber, means responsive to the flow of fuel in said passage for controlling the movement 10 of said air valve comprising a rod connected to said air valve, a conical passage, a disc adapted to move therein, said conical passage being located in the fuel passage leading from the fuel chamber to said fuel nozzle, valve means for admitting air to said fuel passage below said disc, said valve means being operatively connected to said diaphragm.

5. A floatless self feeding carburetor comprising a cylindrical air valve, an air entrance controlled thereby, a mixture chamber, a mixture outlet, fuel supply means comprising a fuel chamber, a fuel entrance leading thereto, a fuel shut off valve in said fuel entrance, a diaphragm located in said fuel chamber and connected to said 20 shut off valve, two fuel passages leading from said fuel chamber to said mixing chamber, means responsive to the flow of fuel in said fuel passages for controlling the movement of said air valve comprising a rod connected to said air valve, two discs located thereon, two conical fuel passages in which said discs reciprocate, said conical fuel passages being located one in each of said two fuel passages, valve means for admitting air to said fuel passages below said discs, said valve 30 means being operatively connected to said diaphragm.

6. A floatless self feeding carburetor comprising a cylindrical air valve, a primary air passage controlled thereby, a mixture chamber, a mixture outlet, a throttle valve therein, fuel supply means comprising a fuel chamber, a fuel entrance leading thereto, a fuel shut off valve in said fuel entrance, a diaphragm located in said fuel chamber and connected to said fuel shut off valve, two fuel 40 passages leading from said fuel chamber to said mixing chamber, means responsive to the flow of fuel in said fuel passage for controlling the movement of said air valve comprising a rod connected to said air valve, two discs located thereon, two conical fuel passages in which said discs reciprocate, said conical fuel passages being located one in each of said two fuel passages, valve means for admitting air to said fuel passages below said discs, said valve 50 means being operatively connected to said diaphragm, throttle controlled means for selectively directing said air alternately to one of said fuel passages for the purpose described.

7. In a floatless self feeding carburetor for an 60 internal combustion engine comprising an air valve, a primary air passage controlled thereby, a fuel entrance, a diaphragm responsive to the pressure in the fuel entrance, a fuel nozzle discharging into the air entrance on said engine side of the air valve, a fuel passage leading from the said fuel entrance to the said fuel nozzle, means responsive to the flow in said fuel passage for controlling said air valve, valve means for admitting air to said fuel passage, said valve 65 being operatively connected to said diaphragm for the purpose described.

8. In a floatless self feeding carburetor, an air valve, a primary air passage controlled thereby, a fuel entrance, a mixture outlet, a throttle valve 70 therein, a fuel nozzle discharging into the primary

air passage on the outlet side of the said air valve, a cylinder, a piston therein operatively connected so as to be raised whenever the throttle is opened, a check valve in said piston, a fuel passage in said piston controlled by said valve, a fuel passage from the fuel entrance to the lower end of said cylinder, a fuel outlet in the lower portion of said cylinder, said fuel outlet being restricted by said piston when the throttle valve is closed, a second fuel outlet from the upper portion of said 10 cylinder, an air passage leading from the atmosphere to said second fuel outlet, a common fuel passage into which both of said fuel outlets discharge, said common fuel passage communicating with said fuel nozzle. 15

9. Accelerating means for a floatless self feeding carburetor having a mixture chamber, a mixture outlet, and a throttle therein, comprising a substantially vertical cylinder, a piston reciprocating therein, a fuel passage through said piston, 20 a check valve therein, means for lifting said piston as said throttle is opened, a fuel outlet from said cylinder located so as to be covered by said piston when the throttle is closed, a second fuel outlet located in the upper part of said cylinder, an air entrance into said second fuel outlet both of said fuel outlets being adapted to discharge into said mixture chamber. 25

10. Accelerating means for a floatless self feeding carburetor having a mixture chamber, a mixture outlet, and a throttle therein, comprising a substantially vertical cylinder, a piston reciprocating therein, a passage through said piston, a check valve therein, means for lifting said piston as said throttle is opened, a fuel outlet from said cylinder located so as to be covered by said piston when the throttle is closed, a second fuel outlet located in the upper part of said cylinder, both of said fuel outlets being adapted to discharge into said mixture chamber. 30

11. Accelerating means for a carburetor having a fuel chamber, a mixture chamber, a mixture outlet and a throttle therein, comprising a substantially vertical cylinder communicating at its lower end with said fuel chamber, a piston reciprocating in said cylinder, a fuel passage through said piston, a check valve therein, means for lifting said piston as said throttle is opened, a fuel outlet from said cylinder located so as to be covered by said piston when said throttle is 40 closed, a second fuel outlet located in the upper part of said cylinder, an air entrance into said second fuel outlet, both of said fuel outlets being adapted to discharge into said mixture chamber. 45

12. Accelerating means for a carburetor having a fuel chamber, a mixture chamber, a mixture outlet and a throttle therein, comprising a substantially vertical cylinder communicating at its lower end with said fuel chamber, a piston reciprocating in said cylinder, a fuel passage through 60 said piston, a check valve therein, means for lifting said piston as said throttle is opened, a fuel outlet from said cylinder located so as to be covered by said piston when said throttle is closed, a second fuel outlet located in the upper 65 part of said cylinder, both of said fuel outlets being adapted to discharge into said mixture chambers.

13. A floatless self feeding carburetor comprising a balanced air valve, a primary air passage controlled thereby, a fuel entrance, a fuel supply passage leading therefrom to said primary air passage on the outlet side of said air valve, means responsive to the flow of fluids in said fuel passage for opening said air valve, means 70

directly responsive to the pressure in said fuel entrance for admitting more or less air to said fuel passage.

14. A carburetor having a mixture chamber and a balanced air valve, a primary air passage controlled by said air valve and leading to said mixture chamber, a fuel entrance, a fuel supply passage leading therefrom to said mixture chamber, a movable obstruction in said fuel passage movable by fuel flowing in said fuel passage and connected to said air valve for moving said air valve, an air passage admitting a relatively small quantity of air to said fuel passage on the upstream side of said obstruction.

15. A carburetor having a mixture chamber and a balanced air valve, a primary air passage controlled by said air valve and leading to said mixture chamber, a mixture outlet, a throttle valve therein, a fuel entrance, a fuel supply passage leading therefrom to said mixture chamber, a movable obstruction in said fuel passage, a relatively small air passage leading to the upstream side of said fuel passage, a second movable obstruction in said air passage, said second obstruction being connected with the first obstruction and with the balanced air valve, throttle controlled means for obstructing the air flow to said air passage when the throttle is closed.

16. A carburetor as described in claim 15 and having two tapered passages in which the two obstructions are moved by the flow of fluid therethrough.

17. A carburetor having a mixture chamber and a balanced air valve, a primary air passage, controlled by said air valve and leading to said mixture chamber, a mixture outlet, a throttle valve therein, a fuel entrance, a fuel supply passage leading therefrom to said mixture chamber, a movable obstruction in said fuel passage, a relatively small air passage leading to the upstream side of said fuel passage, a second air passage also leading to the upstream side of said fuel passage, a second movable obstruction in said second air passage, both of said obstructions being connected with the balanced air valve, throttle controlled means for obstructing the air flow to said second air passage and for admitting the air flow to the first air passage as the throttle is closed.

18. A carburetor as described in claim 17 and having two tapered passages in which the two obstructions are moved by the flow of fluids therethrough.

19. In a carburetor having a mixing chamber and an air entrance leading to said mixing cham-

ber, a fuel nozzle discharging therein, a floating obstruction in said fuel nozzle, a balanced air valve operatively connected to said obstruction, said air valve being adapted to control the air entrance to said mixing chamber, said obstruction adapted to open said air valve as the fuel flow increases due to decrease of pressure in said mixing chamber and a corresponding increase of fuel flow through said nozzle.

20. In a carburetor for internal combustion engines, a mixing chamber, means for controlling the delivery of air to said mixing chamber including an air valve responsive to the suction in the mixing chamber, means for delivering fuel to said mixing chamber from a source of fuel supply, and means including a diaphragm directly responsive to the fuel level in said source for controlling said air valve to provide for progressively closing said valve as said fuel in said source becomes lower.

21. In a carburetor having an air entrance, an air valve therein, a mixing chamber leading out of said entrance, a variable lift fuel supply means connected to said mixing chamber through a fuel passage, means for opening the air valve responsive to an increase of suction in the mixing chamber, and means including a diaphragm directly responsive to an increase of lift in the fuel supply means for closing said air valve.

22. In a carburetor, a primary air entrance having an air valve therein, a mixing chamber leading out of said entrance, a variable lift fuel supply means connected to said mixing chamber through a fuel passage, a secondary air entrance connected to said mixing chamber through an air passage, means responsive to flow of air through said second air passage for opening said air valve, and means responsive to an increase in lift in the fuel supply for closing said second air entrance.

23. In a carburetor for internal combustion engines, a mixing chamber, a primary air entrance for delivering air to said mixing chamber including an air valve, means for delivering fuel to said mixing chamber from a source of fuel supply, a secondary air entrance connected to said mixing chamber through an air passage, means in said air passage responsive to flow of air therethrough for opening said air valve, and means responsive to the fuel level of said source for progressively closing said second air entrance as said fuel level becomes lower to control the opening of said air valve.

WILFRED O. CHASE. 55
